SERVING TOOL

Harry L. Kitselman, Muncie, Ind., assignor to
 Indiana Steel & Wire Company, Muncie, Ind.,
 a corporation of Indiana

Application February 12, 1945, Serial No. 577,503

4 Claims. (Cl. 242—7)

1

It is the object of my invention to produce a serving tool which can be simply and economically manufactured and effectively used in serving joints in wire cables or the like.

In carrying out my invention I employ a rigid rod or wire bent at one end into a U-shaped hook to receive the cables which are to be served. The legs of the hook are desirably of unequal length, the shorter leg being joined to the body of the tool. Such tool-body lies in a plane normal to the parallel legs of the hook and is desirably disposed in such plane at an angle to the plane of the hook. For use with the tool I employ a single-layer coil of wrapping wire having an internal diameter slightly larger than the stock of which the tool is formed.

The accompanying drawing illustrates my invention: Fig. 1 is a plan view of the tool; Fig. 2 is a side elevation of the tool; Fig. 3 is a perspective view illustrating the tool in use in forming an eye on a cable; and Fig. 4 is an elevation of a coil of wrapping wire for use with my tool.

As will be clear from the drawing, the tool is formed of a length of circular rod or wire bent into a U-shape at one end to provide parallel legs 10 and 11 joined by an intermediate curved leg 12. The leg 11 is shorter than the leg 10 and joins the straight body 13 of the tool through a bend 14. Preferably, the body 13 lies in a plane generally normal to the legs 10 and 11, as will be clear from Fig. 1, while the leg 11 is twisted so that the body of the tool will be disposed at an angle to the common plane of the legs 10 and 11, as indicated in Fig. 2. The spacing between the legs 10 and 11 is somewhat greater than necessary to permit the entry between them of the cables or other articles to be served.

The supply of wrapping wire used in association with my tool is in the form of a single-layer, helically wound coil 15. As initially formed, the wire of this coil desirably extends tangentially from one end of the coil for a distance as indicated at 16. The internal diameter of the coil 15 is slightly greater than the diameter of the material from which the tool is formed so that the coil will have a loose sliding fit on the rod. The coil should not fit the rod too tightly for if it does it might collapse and seize the rod under the influence of the tongue it transmits.

When the tool is to be used, a supply-coil 15 is slipped over the outer end of the tool-body 13, that end of the coil from which the wire-stretch 16 extends being applied to the tool-body first. The coil is slipped down the handle-body until its inner end passes around the bend 14; and the

5 tool is then ready for a serving operation. To apply a wrap, the cables 17 or other articles to be served are placed between the two legs 10 and 11 of the hook at the end of the tool, and the projecting wire-stretch 16 is secured to the cables in any convenient way. Then, with the tool-body 13 disposed generally normal to the cables, the tool is rotated about the cables in the direction indicated by the arrow in Fig. 3. As the tool is 10 thus rotated, wire feeds from the supply coil 15 and is wrapped about the cables, the supply-coil rotating on the tool.

The depth of the hook 10—11—12 as measured 15 from the projected axis of the body portion 13 of the tool should be greater than the diameter of the object being served so that with such object seated in the hook the wrap-wire will leave the tool in a direction such that the tension within it will tend to draw the coil 15 along the body 13 and around the bend 14.

The tightness of the wrap produced by my serving tool depends chiefly upon two factors—namely, the diameter of the supply coil and the radius of the bend 14. In passing from the supply coil to the wrap the wire is straightened from the bent condition it occupies in the supply coil, and the effort required to straighten it will vary in a sense opposite to that of the diameter of the supply coil. Therefore, by making the supply 20 coil of relatively small diameter I am enabled to insure a substantial tension in the wire applied to the article being served.

As the feeding of wire to the wrap is accompanied by rotation of the supply coil on the tool-body 13, friction between the supply coil and tool-body will tend to increase tension in the wire. The fact that the supply coil is elastically deformed by reason of its passage around the bend 14 of the tool insures the existence of substantial friction opposing coil-rotation. I have found that the effect of such friction in creating or increasing tension in the wire is dependent upon the curvature of the bend 14; a sharp bend increasing tension and vice versa.

For most purposes, satisfactory tightness of the wrap will be provided if the supply coil has an external diameter no greater than ten times the diameter of the wire composing it and if the bend 14 has a radius, measured at the axis of the rod, of about one and one-half to two times the diameter of the rod.

It will be clear from Fig. 3 that tension in the wire passing from the supply-coil 15 to the wrap tends to rotate the tool about an axis parallel to the legs 10—11 and that this tendency is resisted

by contact of the two legs with opposite sides of the cable-pair being served. The tool is so proportioned that with the legs 10 and 11 drawn into contact with opposite sides of the cable-pair by tension in the wire leaving the supply coil the tool-body 13 will occupy a position generally normal to the cable-pair. With the tool so proportioned, practically no effort on the part of the operator is necessary to secure a tight wrap on the cables being served. In other words, the tool automatically tends to assume a position such that the successive turns of the wrap will be in contact with each other.

I claim as my invention:

1. A serving tool, comprising a round rod having a straight body portion and bent at one end to provide a generally U-shaped hook adapted to receive an article to be served and having two generally parallel legs, said body portion lying approximately in a plane normal to the two legs of said hook and at an angle to the common plane of said legs, said body portion joining the adjacent leg of the hook through a smooth bend, whereby a helically wound coil of wrap-forming wire only slightly larger than said rod may be placed over the body portion and slid therealong to a position in which it extends around said bend and on to the adjacent leg of said hook.

2. A serving tool, comprising a round rod having a straight body portion and bent at one end to provide a generally U-shaped hook adapted to receive an article to be served and having two generally parallel legs, said body portion lying approximately in a plane normal to the two legs of said hook, said body portion joining the adjacent leg of the hook through a smooth bend, whereby a helically wound coil of wrap-forming wire only slightly larger than said rod may be placed over the body portion and slid therealong to a position in which it extends around said bend and on to the adjacent leg of said hook.

3. In a serving means for securing together a plurality of elongated articles in juxtaposed rela-

tion, a single-layer, helically wound coil of wire from one end of which there projects a generally straight stretch of wire adapted to be secured to said articles, the external diameter of said coil being less than ten times the diameter of the wire composing it, an elongated support disposed within and frictionally engaging said coil, said support being bent within the axial limits of the coil and at a point adjacent that end of the coil from which said straight stretch of wire projects to provide increased friction opposing rotation of the coil on the support, said support being provided beyond such coil-end with a hook adapted to receive the articles to be served.

15 4. In a serving means for securing together a plurality of elongated articles in juxtaposed relation, a single-layer, helically wound coil of wire from one end of which there projects a generally straight stretch of wire adapted to be secured to said articles, an elongated support disposed within and frictionally engaging said coil, said support being bent within the axial limits of the coil and at a point adjacent that end of the coil from which said straight stretch of wire projects to provide increased friction opposing rotation of the coil on the support, said support being provided beyond such coil-end with a hook adapted to receive the articles to be served.

HARRY L. KITSELMAN.
